UNITED STATES PATENT OFFICE.

WILLIAM H. WHITE, OF TOUCHET, WASHINGTON.

NAIL PULLER.

Application filed August 29, 1923. Serial No. 659,854.

To all whom it may concern:

Be it known that I, WILLIAM H. WHITE, a citizen of the United States, residing at Touchet, in the county of Walla Walla and State of Washington, have invented certain new and useful Improvements in Nail Pullers, of which the following is a specification.

This invention is in the way of a nail puller, and the object is to provide a simple and efficient tool for this purpose.

In the drawing—

Figure 1 is a side elevation,

Fig. 2 is a plan view, and

Fig. 3 is an end view.

The invention includes a handle 1, at the end of which is affixed a metal hammer head 2, the opposite end of the head being reduced to an inwardly turned nail jaw 3, which is also turned to one side as to the left, as shown in the drawing. A bill 4 is pivoted at 5 medially to the side of the head 2, and has a nail jaw 6 turned inwardly and to one side to meet and cooperate with the other nail jaw 3. The forward end of this bill is extended forwardly in substantial alinement with the handle 1 and formed into an insert point 7 curving upwardly from the foot 8.

In use, the point 7 may be used for insertion under a board for prying and loosen-

ing the same, after which the nails may be grasped between the jaws 3 and 6 and pulled out by elevating the handle 1.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

A device of the kind described, comprising a handle; a hammer head at the end of the handle, the end thereof opposite the head being reduced and turned inwardly and to one side to form a nail jaw; and a bill pivoted to one side of the hammer head, the rear end thereof having a nail jaw turned inwardly and to one side to form a nail jaw to coact with the first-mentioned nail jaw, and the forward end of the bill being extended forwardly in substantial alinement with the handle and being curved upwardly to form an insert point.

In testimony whereof I affix my signature.

WILLIAM H. WHITE.
